UNITED STATES PATENT OFFICE.

GEORGE L. K. MORROW, OF DETROIT, MICHIGAN, ASSIGNOR TO DEXTER M. FERRY, OF SAME PLACE.

MOWING-MACHINE.

SPECIFICATION forming part of Letters Patent No. 339,997, dated April 13, 1886.

Application filed January 29, 1886. Serial No. 190,206. (No model.)

To all whom it may concern:

Be it known that I, GEORGE L. K. MORROW, of Detroit, county of Wayne, State of Michigan, have invented a new and useful Improvement in Mowing-Machines; and I declare the following to be a full, clear, and exact description of the invention, such as will enable others skilled in the art to which it pertains to make and use it, reference being had to the accompanying drawings, which form a part of this specification.

My invention consists of the combination of devices and appliances hereinafter specified, and more particularly pointed out in the claims.

My invention relates more particularly to the pitman-connection between the revolving head at the lower end of the radial arm of a mowing-machine or harvester and the cutter-bar. It is well known that by reason of the plane of rotation of the said revolving head being inclined to the plane in which the cutter is caused to move there is necessitated a universal movement of the extremities of the connecting-pitman.

This invention consists of a novel construction of said connections.

In the drawings, Figure 1 is a view in section illustrating my invention. Fig. 2 is a face view of the upper surface of the rotary head, illustrating how the nut is locked in position.

A represents the lower end of the driving-shaft contained within or supported by the radial arm of a mowing-machine or harvester, and by which motion is communicated from the axle of the machine to the cutter-bar.

B is the rotary head at the lower extremity of said arm.

C is the heel of the cutter-bar or part to which power is applied to reciprocate said bar.

D is the connecting-pitman. This pitman, at the end adjacent to the cutter-bar, is finished in globular form, as shown at d, and has through it a double conical opening, d', as shown, through which is passed a plain round bolt, d'', this bolt being preferably provided with an angular head countersunk into a correspondingly-shaped recess, while at the other end it is provided with a nut, d'', and I prefer, also, to provide the bolt with a through-opening at its threaded end for the reception of a

spring-cotter, d'', for locking the nut against running off from the bolt.

The boxing for the reception of the spherical end of the pitman is as indicated at C and C', likewise of corresponding spherical form within, and are preferably secured in place upon the said spherical head and to the heel of the cutter-bar by the same bolt, d'', although this particular method of securing the boxing to the bar and the parts of the boxing to each other is not absolutely essential. At the other end of the pitman, adjacent to the rotary head B, I shape the pitman into hollow spherical form, as shown at D', passing through the same from the inside a bolt, D'', having the under surface of its head shaped in corresponding spherical form, the spherical end of the pitman having an enlarged opening, D'', for the passage of the bolt, so as to admit of the requisite play when the device is in operation. The said bolt D'' is squared along that portion which passes through the rotary heads, and adapted to fit a corresponding opening, so as to be held from turning. At the other end of the bolt is provided a nut, and the said nut has any suitable means for locking it upon the bolt. The means I prefer to employ for this purpose is to make the bolt with a projecting annular flange, D'', which is provided with 80 ratchets on its under face, and a spring-pawl, D'', engages the said ratchet and prevents the nut from turning. This device is very well adapted for the purpose, since any wear upon the spherical surfaces, either of the rotary head, the pitman, or the bolt itself, may be readily compensated for by taking a slight turn on the nut and locking it in its new position.

I have found that a pitman constructed and connected at its extremities in the manner shown operates with perfect freedom and accomplishes the required purpose in a more perfect manner than the same has been accomplished by devices heretofore employed for a like purpose. The nut d'' at the end of the bolt d'' is preferably provided with radial grooves in its upper surface, so that when the nut is turned down for the purpose of tightening up to compensate for wear on the spherical ball and boxing it may be locked in any desired position by the spring-cotter, which passes through the bolt and rests within the

corresponding groove in the nut, so that the cotter serves not only the purpose of preventing the nut from running off the bolt when in use, but to fix the nut in any desired position.

5. What I claim is—

1. In a mowing-machine or harvester, the combination, with the cutter-bar and inclined rotary head for giving motion to the same, of a pitman formed at the cutter-head end into a spherical ball housed in spherical boxing, the whole secured together by a bolt, d^2 , said pitman at its other end shaped into a hollow hemispherical head seated within a corresponding cavity in the rotary head, and the whole secured by a square stem-bolt, D^2 , with the under surface of its head spherically shaped and adapted to wear against the inner surface of said hemispherical end of the pitman, substantially as described.
- 15 2. As a means for connecting a pitman, D , with the cutter-bar of a mower or reaper, a spherical ball, d , provided with double conical openings, boxing composed of the two parts $C' C^2$, the lower part connected to the cutter-bar, and both parts provided with corresponding spherical-shaped bearings for the ball, and a central bolt passing through said boxing and ball, substantially as described.
- 20 3. The combination, with the pitman D , of the spherical ball at its end, with a double conical opening, boxing composed of two parts, $C' C^2$, the lower part connected to the cutter-

bar, and both parts provided with corresponding bearings, and a bolt passing through the heel of the cutter-bar, the boxing, and the ball, 35 and provided with a nut at its upper end, said nut capable of adjustment to compensate for wear upon the boxing and ball, substantially as described.

4. The combination, with the pitman D and the rotary head B , of a hollow hemispherical head at the end of the pitman, a corresponding recess in the rotary head, a square stem-bolt provided with spherical-shaped bearings beneath its head, and a nut for holding the 40 parts in place, substantially as described.

5. The combination, with the pitman D and the rotary head B , of the hemispherical end of the pitman, the bolt D^2 , and nut at its end, 50 said nut adapted to be adjusted to any desired degree and locked in any position, substantially as described.

6. The combination, with the hemispherical end of the pitman formed with the enlarged slots D^3 , the rotary head, and square stem-bolt D^2 , the nut provided with a ratchet-face and spring-pawl, substantially as and for the purpose described.

In testimony whereof I sign this specification in the presence of two witnesses.

GEORGE L. K. MORROW.
